UNITED STATES PATENT OFFICE.

JOSEPH A. BENNETT, OF HARTFORD, CONNECTICUT, ASSIGNOR TO CHARLES H. A. F. L. ROSS, OF BALNAGOWAN CASTLE, COUNTY OF ROSS, SCOTLAND.

FIREARM.

SPECIFICATION forming part of Letters Patent No. 643,935, dated February 20, 1900.

Application filed September 20, 1899. Serial No. 731,084. (No model.)

To all whom it may concern:

Be it known that I, JOSEPH A. BENNETT, a citizen of the United States, residing at Hartford, in the county of Hartford and State of Connecticut, have invented new and useful improvements in Firearms, of which the following is a specification.

In the following specification and in the accompanying drawings I have shown my invention as applied to a straight-pull breech mechanism of the general character of that described in the application of Charles H. A. F. L. Ross for improvements in firearms, filed in the United States Patent Office on the 15 29th day of December, 1897, and serially numbered 664,364, although my invention in several of its features is broad enough to cover the use of such features with breech mechanisms other than the straight-pull type.

20 This invention more particularly relates to means for securing the firing-pin in place, whereby it may be readily dismounted without the use of tools; to means for preventing the jarring open of the breech, which has heretofore happened when guns of the breech-bolt type have been roughly handled, as at drill; to means for locking the firing-pin in its normal position, and in a safety-lock for engaging the firing-pin when the latter has 25 been retracted, thus preventing accidental discharge of the gun, in combination with the breech-lock.

The several devices heretofore referred to will be described in detail with reference to 30 the annexed drawings, in which—

Figure 1 is a plan view of my improved breech mechanism shown as closed, parts of the receiver and gun-stock being broken away for the purpose of illustrating the construction of the ejector. Fig. 2 is a transverse section on lines X X of Fig. 1. Fig. 3 is a side elevation, partly in section, with the firing-pin retracted. Fig. 4 is a perspective view of the safety-lock latch. Fig. 5 is a longitudinal section through the breech-bolt and firing-pin contained therein. Fig. 6 is a perspective view of the cocking-head nut. Fig. 7 is a perspective view of the catch-head.

The barrel 1 is secured to the forward end 35 of the receiver 2, provided with the guiding-grooves and locking-shoulders common to

straight-pull breech mechanism. The breech-piece, comprising the sleeve 2^a, hollow breech-bolt 3, and firing-pin 4 and parts operating in connection therewith, moves longitudinally 55 in the receiver, the construction of the parts being such that the breech-bolt is rotated to lock the breech closed by the forward movement of the sleeve and is rotated in a reversed direction to unlock the breech by a rearward 60 movement of the sleeve.

The firing-pin 4 extends axially through the breech-bolt and is driven forwardly therein by a coiled spring 5, interposed between a shoulder upon the firing-pin and a screw-plug 65 6, with a milled head 7 closing the rear of the bore of the breech-bolt. A suitable extractor (not shown) is mounted on and moves with the sleeve, while a spring-pressed ejector 9 projects through the receiver into the path of 70 the cartridge when the latter is drawn back by the extractor and throws the fired shell out of the receiver.

The several parts hereinbefore referred to are well known in the art, and therefore need 75 no detailed description, except in so far as they may have been modified in adding them to my present invention.

The firing-pin 4 projects rearwardly through the plug 6 of the breech-bolt to receive the 80 catch-head and cocking-head. The catch-head 10 has a shoulder 11 thereon provided with full-cock and safety-stop notches 12 and 13, respectively, and is slid upon the firing-pin, the parts having a flattened face 14 to 85 prevent relative rotation. The forward end of the central aperture of the catch-head is counterbored to receive a spiral spring 14^a, the forward end of which bears against a washer 15, interposed between it and the rear 90 face of the screw-plug 6. The catch-head is secured in place by the cocking nut or head 16, which is mounted upon the threaded rear end of the firing-pin and serves as a handle to permit the pin to be cocked. For the purpose of holding the cocking head or nut against working off the firing-pin under the jars to which it is subjected I provide the forward end thereof with a radial groove 17, adapted to receive a corresponding radial 95 shoulder upon the rear end of the catch-head when the nut has been turned fully home. 100

In practice I provide several radial grooves 17 in order to permit the described engagement to take place at a plurality of points on each rotation of the nut. In screwing up or 5 taking off the nut the catch-head may be moved forwardly on the firing-pin by engaging the projecting shoulder 11 thereof, compressing the spring 14^a and disengaging the radial rib and groove. When the nut has 10 been brought to the desired point, the catch-head may be released and the spring 14^a will again force the shoulder and groove into engagement, thus locking the parts together and preventing the accidental loosening of 15 the cocking head or nut.

To prevent the accidental opening of the breech, I cut in the rear part of the sleeve a transverse slot 19 and pivot therein a latch 20, the shape of which is shown in detail in 20 Fig. 4. In the normal position of the latch-piece in the slot the face 20^a thereof registers with the side face 2^b of the sleeve; but when the latch-piece by means of its nose 20^b is manually thrown over to the position shown 25 in dotted lines in Fig. 2 its tail 20^c enters a vertical slot 21 in the wall of the receiver and by engaging the face formed thereby prevents the movement of the sleeve in the receiver. I also make use of this movement of 30 the latch to lock the firing-pin in its normal position, and this I accomplish by extending the slot in the sleeve down to the central bore thereof and by forming upon the latch a curved face 20^d, which in the normal position 35 of the latch registers with the inner wall of such bore, so that the catch-head contained within such bore may move freely. A second tailpiece 20^e is formed upon the latch, and upon the movement of the latch to engage the 40 receiver, as before described, this tail enters a notch 22 in the catch-head and prevents the firing-pin from being retracted. As the catch-head is in this construction necessarily contained within the rear end of the sleeve, 45 the shoulder 11 upon the former is extended through a longitudinal slot 11^a in the lower side of the sleeve into proximity with the sear 23. I also utilize the latch for the purpose of affording a safety-catch to prevent the 50 accidental release of the firing-pin when it has been retracted, and this is effected upon throwing the latch over to engage the receiver by the engagement of the tail 20^c with the forward face of the catch-head, the firing-pin 55 having been moved rearwardly. To prevent the discharge of the gun upon the release of the latch and pin, which might otherwise result if the trigger were pulled while the latch was in its locking position, I form upon the 60 tail 20^c of the latch and the front end of the cocking-head inclined faces 20^e and 10^a, respectively, whereby as the latch is thrown into locking position the faces act to cam the firing-pin slightly to the rear, thus relieving 65 the sear of pressure in order that should it be moved while the pin is locked it will meet with no frictional resistance in moving back

into full engagement with the full-cock notch 12 upon the head.

For the purpose of holding the latch in either 70 of the positions in which it may be manually set (shown in full and dotted lines in Fig. 2) I provide on the latch a face 20^f, inclined to the face or tail 20^c and at their junction forming a shoulder 20^g, and, forming a suitable recess 20^h in the sleeve, insert therein a spring-pressed pin 20ⁱ, the pin bearing against one 75 or the other of the faces 20^c 20^g and preventing the latch from being jarred from the position in which it may have been set, but at 80 the same time yielding to permit the passage past it of the shoulder 20^g when the latch is manually thrown.

For the purpose of reducing the space occupied by the ejector I prefer to insert in the 85 tail of the ejector and in the rear of its pivot 24 one end of a flat spring 25, the body of which lies in a longitudinal groove 26, formed along the outer side wall of the receiver. By this construction all extension of the ejector 90 beyond the receiver is prevented except the slight swell at the pivotal point, the nose of the ejector extending forwardly from the pivotal point through a slot 27 in the wall of the receiver.

Having thus described my invention, what I claim, and desire to secure by Letters Patent, is—

1. The combination with a firing-pin, of a catch-head mounted thereon and locked 100 against rotation, a cocking-nut threaded upon the firing-pin, the nut and head having engaging ribs and grooves, and a spring for forcing the catch-head against the nut, substantially as described.

2. The combination with a firing-pin, of a catch-head carried upon the pin and held from rotation thereon, the forward end of the catch-head being counterbored, a spring contained within the counterbored end of the catch-head, and a cocking-nut threaded upon the firing-pin in the rear of the catch-head, the catch-head and nut being provided with engaging ribs and recesses to prevent the rotation of the nut, substantially as described.

3. The combination in a straight-pull breech mechanism with a recessed receiver, of a sleeve, and a movable latch mounted on the sleeve and adapted to engage the recess in the receiver when the breech is closed, substantially as described.

4. In a straight-pull breech mechanism the combination with a receiver having a locking-face thereon, of a sleeve sliding longitudinally in the receiver, a firing-pin contained in the sleeve and having a locking-face thereon, and a latch pivoted in the sleeve and adapted to engage simultaneously the locking-faces in the receiver and firing-pin when the parts are in their normal position, substantially as described.

5. The combination with a receiver having a locking-face thereon, of a sleeve sliding in the receiver, a firing-pin sliding in the sleeve

and having locking-faces thereon corresponding to full-cocked and normal positions, and a latch pivoted to the sleeve and adapted to engage the locking-face in the receiver and either of the locking-faces upon the firing-pin, dependent upon the position of the latter, substantially as described.

Signed by me at Hartford, Connecticut, this 12th day of September, 1899.

JOSEPH A. BENNETT.
